UNITED STATES PATENT OFFICE.

EDWARD W. HATCH, OF BOSTON, MASSACHUSETTS.

FIRE-EXTINGUISHER BRACKET.

Application filed November 1, 1921. Serial No. 512,040.

To all whom it may concern:

Be it known that I, EDWARD W. HATCH, a citizen of the United States, residing at Boston, in the county of Suffolk, State of 5 Massachusetts, have invented a new and useful Fire-Extinguisher Bracket; and I do hereby declare the following to be a full, clear, and exact description of the invention, such as will enable others skilled in 10 the art to which it appertains to make and use the same.

The invention relates to supporting brackets for fire extinguishers of the type which discharge when inverted, and has for 15 its object to provide a bracket of this character which is pivotally mounted on a bearing to one side of the vertical center line of the fire extinguisher and the bracket and held in vertical position by a fusible member, which member when subjected to heat 20 fuses and allows the bracket and the fire extinguisher to pivot downwardly by gravity to an inverted position, and to a position where the fire extinguisher will discharge 25 its contents.

A further object is to provide a bracket with spring clips, which receive and hold the nozzle end of the discharge pipe carried by the fire extinguisher, thereby causing an 30 upward discharge of the fluid from the fire extinguisher.

With the above and other objects in view, the invention resides in the combination and arrangement of parts as hereinafter set 35 forth, shown in the drawings, described and claimed, it being understood that changes in the precise embodiment of the invention may be made within the scope of what is claimed; without departing from the spirit 40 of the invention.

In the drawings:—

Figure 1 is a front elevation of the bracket, showing a fire extinguisher disposed therein and held in normal vertical position.

Figure 2 is a vertical sectional view through the bracket showing a fire extinguisher held therein, said section being taken on line 2—2 of Figure 1.

Figure 3 is a top plan view of the bracket.

Figure 4 is a detail perspective view of a portion of the bracket and the fusible bracket holding member.

Figure 5 is a detail sectional view taken on line 5—5 of Figure 1.

Referring to the drawings, the numeral

1 designates a plate adapted to be secured by means of screws 2 to a wall 3. Plate 1 substantially centrally thereof is provided with a boss 4 extending outwardly from said boss and in a horizontal position is a supporting arm 5, the upper side of which arm is provided with a knife edge 6. The arm 5 extends through an aperture 7 in a bracket 8, which bracket is normally supported on the knife edge 6 of the arm, thereby forming a bearing on which the bracket 8 will easily pivot to an inverted position. The aperture 7 is disposed to one side of the vertical center of the bracket 8 and therefore it will be seen that the bracket when released will swing downwardly in the direction of the arrow *a* to an inverted position. Bracket 8 is provided with a downwardly extending projection 9, the inner face of which is provided with a lug 10, which is spaced from the plate 1. Pivotally connected at 11 to the plate 1 is a holding arm 12, which arm comprises members 13 and 14 which are held together by means of fusible material 15. The member 14 of the arm 12 is provided with an aperture 16 which receives the lug 10 of the projection 9, and consequently allows the arm 12 to prevent pivotal action of the bracket 8. In case of fire the heat within a room or building will cause the fusible material 15 to fuse, thereby allowing the pivoted bracket 8 to pivot downwardly in the direction of the arrow *a* until it assumes an inverted position to that shown in Figures 1 and 2, 85 the purpose of which will suddenly appear.

The bracket 8 at a point above the pivotal point thereof is provided with a socket 17, which socket receives the lower end 18 of the fire extinguisher 19. The fire extinguisher 19 is of that type which when inverted discharges the contents thereof through a flexible discharge hose 20 having a nozzle 21 when the fire extinguisher is turned upside down. The bracket 8 is provided with set screws 22 which hold the fire extinguisher in the socket 17 during the inverting operation and consequently hold the fire extinguisher in operative position after it has been inverted. Fire extinguishers as at present constructed have a flexible hose section 20; therefore to direct the contents of the fire extinguisher 19 upwardly after the same has been inverted, spring clips 23 are provided, which clips 100 105 110

receive and hold the nozzle 21 in such a manner that after the fire extinguisher 19 has been inserted the discharge end of the nozzle will point upwardly, thereby allowing the fluid to discharge from the fire extinguisher in the direction where it will in its fall be spread over large area.

The invention having been set forth what is claimed as new and useful is:—

- 10 1. A supporting bracket for an invertible fire extinguisher, said bracket comprising a plate, a fire extinguisher receiving member horizontally pivoted to said plate at a point off center, means for detachably securing the fire extinguisher to the fire extinguisher receiving member at a point above its pivotal point, a downwardly extending arm carried by the fire extinguisher receiving member and disposed below its pivotal point, a fusible member pivotally connected to the plate, a lug carried by the downwardly extending arm and adapted to enter an aperture of the pivoted fusible member, the pivotal point of the fire extinguisher receiving member being at one side of the center line thereof thereby allowing

the device as a whole to assume an inverted position upon fusing of the fusible member.

2. A supporting bracket for invertible fire extinguishers, said bracket comprising a 30 plate, a horizontally disposed arm carried by said plate and having its upper edge provided with a knife blade bearing, a fire extinguisher receiving and holding bracket mounted on said arm, means for detachably 35 securing said fire extinguisher to said holding bracket at a point above the horizontally disposed arm, a downwardly extending arm carried by said holding bracket, a fusible member connecting said downwardly extending arm to the plate and means carried by the holding bracket for holding the nozzle of the discharge pipe of the fire extinguisher when the same is inverted by gravity. 45

In testimony whereof I have signed my name to this specification in the presence of two subscribing witnesses.

EDWARD W. HATCH.
